UNITED STATES PATENT OFFICE.

WALTER J. TENNENT, OF NORFOLK, VIRGINIA.

DESIGN FOR A SHIELD, BADGE, BUTTON, PIN, OR SIMILAR ARTICLE.

55,965.

Specification for Design.

Patented Aug. 3, 1920.

Application filed June 20, 1917. Serial No. 175,828. Term of patent 3½ years.

To all whom it may concern:

Be it known that I, WALTER J. TENNENT, a citizen of the United States, residing at Norfolk, in the county of Norfolk and State of Virginia, have invented a new, original, and ornamental Design for Shields, Badges, Buttons, Pins, or Similar Articles, of which the following is a specification, reference being had to the accompanying drawing, forming part thereof.

The figure of the drawing is a front elevation of a shield showing my new design.

Referring to the drawing, the shield illustrated has field of blue spangled with white stars extending across the upper end of the shield. Below the blue field are alternate vertical stripes of red and white.

An eagle, represented in flight, has its

wings spread across the blue field hiding parts of the stars. The head of the eagle is directed toward one vertical edge of the shield and adjacent its beak there is one end of a scroll.

The scroll extends from the beak of the eagle downwardly and then beneath the eagle and across the vertical stripes of red and white but terminates a distance from the other vertical edge of the shield.

A bar extends across the stripes between the lower edge of the shield and the scroll.

I claim:

The ornamental design for a shield, badge, button, pin, or similar article, as shown and described.

In testimony whereof I affix my signature.

WALTER J. TENNENT.
